UNITED STATES PATENT OFFICE.

CHARLES W. SMITH, OF NORWALK, OHIO.

DESIGN FOR A CURTAIN-POLE BRACKET.

SPECIFICATION forming part of Design No. 22,296, dated March 14, 1893.

Application filed February 18, 1893. Serial No. 462,921. Term of patent 7 years.

To all whom it may concern:

Be it known that I, CHARLES W. SMITH, a citizen of the United States, residing at Norwalk, in the county of Huron and State of Ohio, have invented certain new and useful Improvements in a Design for Curtain-Pole Brackets; and I do declare the following to be a full, clear, and exact description of the invention, such as will enable others skilled in the art to which it appertains to make and use the same, reference being had to the accompanying drawings, and to the letters of reference marked thereon, which form a part of this specification.

Figure 1 is a side view of a bracket showing my design. Fig. 2 is a view at right angles thereto.

The leading feature of my design consists in the general appearance of the bracket, the same having the appearance of a substantially triangular bracket which at one angle thereof comprises a circular portion.

Referring to the drawings by letter A designates the upright which is surmounted by the portion B which is flattened upon one side and at its top has a suitable ornamentation *a*. Near its lower end the upright has a circular enlargement *b* below which is a substantially acorn-shaped ornament *c*. Joined to the curved portion B is a ring portion C 30 which is joined to the enlargement *b* by the inclined portion D which has the ornaments *d*.

What I claim is—

The design for a bracket substantially as shown and described.

In testimony whereof I affix my signature in presence of two witnesses.

CHARLES W. SMITH.
